(57) **CLAIM**

The ornamental design for a footwear outsole, as shown and described.

DESCRIPTION

FIG. 1 is a bottom perspective view of a footwear outsole showing my new design;

FIG. 2 is a left side elevational view thereof;

FIG. 3 is a right side elevational view thereof;

FIG. 4 is a bottom plan view thereof;

FIG. 5 is a top plan view thereof;

FIG. 6 is a front elevational view thereof; and,

FIG. 7 is a rear elevational view thereof.

The broken lines immediately adjacent to the solid lines in FIGS. 1-3 & 5-7 represent the unclaimed boundary of the design while the broken lines showing the remainder of the footwear outsole and boot throughout the views, illustrate the portions of the design that form no part of the claim.
